MATRIX-SHEET AND METHOD OF PRODUCING SAME.

1,112,356.

Specification of Letters Patent.

Patented Sept. 29, 1914.

Application filed December 4, 1911. Serial No. 663,899.

To all whom it may concern:

Be it known that I, EDGAR R. BULLARD, a citizen of the United States of America, and resident of Wheeling, county of Ohio 5 and State of West Virginia, have invented certain new and useful Improvements in Matrix-Sheets and Methods of Producing Same, of which the following is a specification.

10 This invention relates broadly to matrix sheets, and specifically to a matrix-forming board, card, or sheet, and to the method of producing the same.

The primary object of the invention is 15 to provide a material whereon artists' sketches, drawings, and the like may be initially drawn or applied and which may be employed as a matrix in the process of stereotyping.

20 A further object is to provide a drawing or sketching sheet of the character mentioned whose face is indented with myriads of minute pits, more or less regularly formed and spaced apart, between which

25 pits are minute unindented portions, or undisturbed surface or relief elevations, a stippled or screen-like face being thus formed which negatively corresponds to the face of a half-tone plate.

30 A still further object is to provide a card or plate of which the aforementioned stippled sheet forms the face wherein are provided multitudes of inclosed air pockets which readily yield or break down under 35 the pressure of a pencil, stylus, or type, allowing the material of said sheet to be depressed by such instruments to or below the level of the pits therein without disturbing the adjacent relief portions of the field con-

40 stituted by the sheet. And a still further object within the contemplation of this invention is to structurally improve and render more efficient that character of matrix sheets exemplified in United States Letters 45 Patent to Morningstar, No. 891,499, dated June 23, 1908.

With these and other objects in view, this invention resides in the features of construction, arrangement of elements, combinations of parts, and in the method of making which will hereinafter be fully described, reference being had to the accompanying drawings, forming a part of this specification, in which—

55 Figure 1 is a top plan view, greatly en-

larged, of a portion of a card or board embodying the invention, the letter P being shown impressed thereon to represent a heavy pencil line; Fig. 2 is a transverse section of an unlined portion of the stippled sheet, unmounted, still further enlarged; and Fig. 3 is a similar section of the invention taken on the line 3—3; Fig. 1.

Referring to said drawings, in which like designating characters distinguish like parts throughout the several views 1 indicates generally a sheet of material, preferably of a high grade bond paper of about 20-pound folio, which is substantially covered with extremely minute indentations or 60 pits 2 of pyramidal or cone shape produced by appropriate means, as, preferably, by a metal plate or roll applied under pressure to the sheet, the face of said plate or roll having myriads of minute projections which 65 are preferably regularly shaped and spaced. The sheet is thus embossed, presenting alternate elevated or relief ridges or lines 3 and indentations or pits 2.

The sheet 1 is firmly mounted, after being embossed, upon a base or backing 4 of suitable material, which, while having a surface that is slightly yieldable under pressure, is relatively firm and stiff, the material preferably employed for such base 80 or backing being a cardboard blank of about 8-ply. A suitable cement or adhesive substance 5 is employed as a mountant, a thin coating or film thereof being applied to the base or backing, after which the matrix 85 sheet 1 is placed thereon and is pressed or rolled for causing the downwardly directed apices 6 of the sheet to sink into, or become embedded in, the adhesive substance, as shown in Fig. 3. Inclosed air 90 spaces or pockets 7 are formed between the mountant and the inclined walls defining the pits or indentations 2, there being thus constituted innumerable minute pneumatic cushions which are readily sensitive to the 95 pressure of the artist's pencil. When the pockets 7 become partially or entirely filled with the adhesive substance, as sometimes happens, when, through carelessness, it has been applied too thickly in spots or streaks, 100 the same is in such cellular condition that but little increase in pressure is required to depress or break down the covering walls.

The exposed surface of the card, formed 110

as above described, is, as will be readily understood, soft and yielding, and is readily depressed by the point of a pencil, stylus, or other drawing or sketching instrument, or by the face of type, or cuts, to the level of the pit-formed apices 6.

In practice, slightly more than the slight pressure required to break down or depress the relief surface or lines 3 and the walls defining the pits is preferably applied in order that the point of the pencil or other instrument may depress the material to or slightly below the level of the upper surface of the base or backing 4, thus forming in the matrix a clearly defined line or depression, as shown at 8. The points or indentations in the face of the matrix sheet are of substantially uniform depth and are extremely small and close together, there being about sixty-nine to the inch. Hence, the stereotype, which is produced therefrom by pouring molten metal thereover, as in casting from a matrix in the ordinary or usual manner, has practically the same uniform screen-like lines or dots for producing the well known stippled and lined effect of a half-tone cut. Drawings, pictures and the like for reproduction, as for newspaper and magazine cuts, may be readily made directly upon the face of the matrix sheet, the surface not being roughened by the alternate pits or indentations and relief elevations to such an extent as will retard or appreciably interfere with the movement of the point of the drawing or sketching instrument thereover. The drawing may be made directly upon the matrix sheet, or may be applied thereto by tracing, as by means of an interposed carbon sheet, or in any other manner by which the lines of the drawing may be impressed in the sheet. It will be understood that when a sheet of paper, as a good quality of bond, is employed in the formation of the matrix sheet, the embossing process to which it is subjected does not materially break the texture or effect the separation of the fibers thereof to an objectionable extent. The artist's pencil or drawing instrument passed over the matrix sheet merely acts to depress the elevated or relief surface to or below the level of the pits or indentations, which action is accomplished without breaking or otherwise injuring the texture of the sheet and also without spreading or dis-

turbing action—that is, without filling in or changing the indentations or surfaces adjacent to the artist's lines of depression.

Having thus described my invention, what I claim as new, and desire to secure by Letters Patent, is—

1. A matrix sheet comprising a thin sheet of readily impressionable material which is embossed by indentations extending therethrough to present a working surface having alternate minute stiples in depression and relief lines, said sheet having its reverse face cemented to a base of relatively firmer material having a yieldable surface in such manner that minute air pockets are constituted between said base and the relief elevations, whereby a pliant working surface is provided whereon lines may be impressed without disturbing adjacent lines or stiples. 75

2. The herein described method of forming a matrix sheet, which consists, first, in embossing a sheet of fibrous tissue to produce on its working face a field of minute stiples in depression and interposed relief lines in elevation, second, in mounting the reverse face of said sheet upon a base of a relatively firmer yieldable material so that air-containing pockets are formed between said base and the walls defining said relief lines, and then depressing some of the elevated lines to or below the level of the stiples to form in said sheet a desired design. 80

3. The herein described method of forming a matrix sheet, which consists, first, in embossing through a sheet of thin paper to produce on its working face a field of minute substantially conical stiples in depression and interposed relief lines, second, in mounting said embossed sheet upon a relatively heavier and firmer base so that only the apices of the stiples engage said base and so that air-containing pockets are formed between said base and the walls defining the relief lines, and then breaking down portions of said relief lines to produce a desired design in depression on said working face of the embossed sheet. 95

In testimony whereof I affix my signature in presence of two subscribing witnesses.

EDGAR R. BULLARD.
